MODEL

Peter Copeland and Lillian L. Greneker, New
York, N. Y.

Application July 7, 1936, Serial No. 89,272

3 Claims. (Cl. 223—66)

This invention relates generally to display figures of the human body, but more specifically to display heads or dummies to exhibit articles of dress and adornment and to exhibit qualities of make-up and head-dress.

The main object of the invention resides in the provision of a dummy-head which lends itself to special mounting on display stands resulting in a saving of space and facility of removal.

Another object of the invention resides in the provision of a dummy-head of the above nature which is capable of being water colored and which at the same time produces interesting and attractive light and shade effects when illuminated from the rear.

These objects and other incidental ends and advantages of the invention will hereinafter be set forth in the progress of the disclosure and as pointed out in the appended claims.

Accompanying this specification is a drawing showing preferred forms of the invention and wherein corresponding reference characters indicate corresponding parts throughout the several views.

In accordance with the drawing:

Figure 1 is a rear view in perspective of one type of dummy-head being hollow and showing reinforcing elements thereon.

Figure 2 is a forward view of Figure 1 in perspective, part of the face showing patches of material adapted to receive water colors.

Figure 3 is a cross sectional view of Figure 1 along the plane 3—3 thereof.

Figure 4 is a rear view in perspective of a solid or molded dummy-head partially in section showing a counterweight.

Figure 5 is a front view of Figure 4 in perspective showing one form of a covering therefor.

Figures 6, 7 and 8 show some of the means of mounting the dummy-head on a display platform.

In accordance with the invention and in accordance with the preferred forms thereof shown in the drawing, the dummy-head in Figures 1, 2, 45 and 3 is shown as being hollow and made up of wire screening. Accordingly, the dummy-head is comprised of a face portion 10 and a skull portion 11 suitably secured together. The face portion 10 is provided with the usual anatomical elements such as eyes, nose and mouth. The lower edge of the skull portion 11 is above the bottom of face portion 10 and is preferably in the horizontal plane in order to engage with the upper flat surface 21 of a display platform. A 50 reinforcing element 13 is secured to the lower

edge of skull portion 11 in the form of a wire or band. The rear edge of face portion 10 is disposed inwardly of the rear of skull portion 11 and is preferably in a vertical plane, the said rear edge having a similar reinforcing element 12. The planes of the lower edge of skull portion 11 and the rear edge of face portion 10 meet at an angle to form the engaging means for the positioning thereof on the upper surface 21 and the vertical edge 22 of the display platform. Reinforcing element 12 is secured to face portion 10 by crimping the projecting edges of the face portion 10 at the rear edges thereof therearound, while reinforcing element 13 is secured to skull portion 11 at the lower edge thereof by similarly crimping the projecting wires of skull portion 11 therearound. The forward edges of skull portion 11 are crimped around the reinforcing element 12 for securing the skull portion 11 to the face portion 10. Reinforcing element 13 at the ends 20 thereof is secured to reinforcing element 12 by being hooked as shown in Figure 3.

Where the hollow dummy-head is not made up of wire screening, but of composition, the head and skull portion may be integrally formed or molded so that it becomes necessary to provide a reinforcing element for the rear edge of face portion 10 only below the plane of the lower edge of the skull portion 11.

The hollow dummy-head above described may have its face portion covered with material which is capable of receiving water colors for purposes of enlivening the facial features. This covering may assume the form of paper patches as shown in Figure 2. It is, of course, understood that any other substitute covering for paper patches 30 is feasible, so long as the said covering will take to water colors. The hollow dummy-head thus far described is capable of producing interesting and attractive light and shade effects when illuminated from the rear, especially where the dummy-head is made up of wire screening.

The skull portion of Figures 1, 2, and 3 may be provided with a weight 14 preferably secured along the surface thereof to bring the center of 45 gravity of the dummy-head more to the rear of the skull region, so that when mounted, the head will not fall off the platform.

Figures 4, 5, 6, 7, and 8 show a solid dummy-head 16 molded in one piece and having a rear 50 angular cut-out illustrated by horizontal and vertical surfaces 18 and 19. 19' indicates a curved surface in place of a plane surface in order to engage with a circular or rounded platform. A weight 17 is secured within the skull portion 16 55

for counterbalancing purposes so that the dummy-head, when mounted on a platform, will not tilt forward or lose its equilibrium. Dummy-head 16 is provided with a similar covering, such as 20, 5 to permit application of water colors to the face portion thereof. Figure 8 shows the dummy-head 16 mounted on an upright 23, the said upright 23 engaging with a bore 24 therein.

The dummy-heads above described can be used 10 for exhibiting ladies' and men's hats, coiffure, and the art of cosmeticians. The heads are mountable on platforms of manifold shapes and are designed to take up little space and to be easy of removal.

15 We wish it understood that minor changes and variations in the location and number of parts, in the construction, integration, connection and operation of the several parts, may all be resorted to without departing from the spirit of the invention and without departing from the scope of the 20 appended claims.

We claim:

1. A display dummy-head adapted to be removably engaged with the edge of a display platform, comprising a skull portion and a face portion, the lower edges of the rear end of the skull portion being substantially in a horizontal plane above the bottom of the face portion, the rear edges of the face portion being substantially in 25 a vertical plane and lying inwardly of the rear end of the skull portion and meeting the lower edges of the rear end of the skull portion to form 30 a seat portion whereby the head is supported intermediate the top and bottom of the face portion in a substantially perpendicular engaging 35

angle for the edge of said display platform, and a weight member secured at the rear end of the skull portion to serve as a counterbalance.

2. A display dummy-head adapted to be removably engaged with the edge of a display platform, comprising a skull portion and a face portion, the lower edges of the rear end of the skull portion being substantially in a horizontal plane above the bottom of the face portion, the rear edges of the face portion being substantially in 10 a vertical plane and lying inwardly of the rear end of the skull portion and meeting the lower edges of the rear end of the skull portion to form a seat portion whereby the head is supported intermediate the top and bottom of the face portion in a substantially perpendicular engaging 15 angle for the edge of said display platform, and patched covering material secured to the face portion adapted to receive water colors thereon.

3. A display dummy-head adapted to be removably engaged with the edge of a display platform, comprising a skull portion and a face portion, the lower edges of the rear end of the skull portion being substantially in a horizontal plane above the bottom of the face portion, the rear edges of the face portion being substantially in 20 a vertical plane and lying inwardly of the rear end of the skull portion and meeting the lower edges of the rear end of the skull portion to form 25 a seat portion whereby the head is supported intermediate the top and bottom of the face portion in a substantially perpendicular engaging 30 angle for the edge of said display platform.

PETER COPELAND.
